UNITED STATES PATENT OFFICE.

CHARLES P. RUBLEY, OF NEWARK, NEW JERSEY, ASSIGNOR TO MERGENTHALER LINOTYPE COMPANY, A CORPORATION OF NEW YORK.

TYPOGRAPHICAL MACHINE.

1,119,542.

Specification of Letters Patent.

Patented Dec. 1, 1914.

Application filed December 5, 1912. Serial No. 735,067.

To all whom it may concern:

Be it known that I, CHARLES P. RUBLEY, a citizen of the United States, and a resident of Newark, county of Essex, and State of New Jersey, have invented a new and useful Improvement in Typographical Machines, of which the following is a specification.

My invention relates to typographical machines, such as linotype machines of the general organization represented in Letters Patent of the United States, No. 436,532, to O. Mergenthaler, wherein circulating matrices are released from a magazine in the order in which their characters are to appear in print and then assembled in line, the composed line transferred to the face of a mold, the mold filled with molten metal to form a slug or linotype against the matrices which produce the type characters thereon, and the matrices thereafter returned through a distributing mechanism to the magazine from which they started.

More particularly, it relates to the distributing mechanism, etc., as illustrated in said patent or as employed in the commercial linotype machine, wherein the matrices are conveyed to the distributing mechanism by a carrier ordinarily known as the "second elevator."

In the actual operation of these machines, it sometimes occurs that a matrix is reversed in the line, or that one of another font is contained therein, which should be removed before the line is distributed. This is ordinarily done by the operator, and it is desirable that the elevator be maintained in its upper or operative position during the operation. As the manipulation of the wrong or misplaced matrix is most conveniently effected by both hands, it is the purpose of my invention to relieve the operator from the necessity of manually holding the elevator during the operation. To this end, I provide a locking means, preferably in the form of a latch connected to the elevator, whereby it may be held temporarily in position and thus leave both hands free for the removal or shifting of the offending matrix.

In the accompanying drawing, I have shown my invention in preferred form and by way of example, and as applied to the style of machine referred to, but obviously many variations and modifications thereof,

and in its mode of application, will be possible without departure from its spirit. 55 Thus, it may be applied to other forms of typographical machines, such as typesetters, typecasters or the like, or to machines which handle type or dies instead of matrices. Generally speaking, I desire it to be understood that I do not limit myself to any specific form or embodiment, except in so far as such limitations are specified in the claims.

Referring to the drawing: Figure 1 is a 65 rear view of a portion of the distributing mechanism, etc., illustrating my invention; Fig. 2 is a similar view showing the parts in different position; and Fig. 3 is a transverse sectional view through the latch. 70

As is usual in this style of machine, the matrices X are transported by the second elevator G to the distributor box A, into which they are moved by the transfer device B. Fig. 1 shows the elevator slightly 75 before it has reached its final position, and Fig. 2 shows it therein. The elevator G is provided with the pivoted finger-latch H, which is operable at will, to engage the stationary frame-work, as for instance the 80 notch C, to lock the elevator in its active position, and thus to allow the operator the free use of both hands for any desired manipulation of the matrices or other parts.

As previously stated, I have shown my invention in preferred form and by way of example, but obviously many alterations and modifications thereof, and in its mode of application, will suggest themselves to those skilled in the art and still be comprised within its scope. Thus, it may be applied not only to other forms of typographical machines, but also to other parts thereof, or in fact wherever it may be required to hold a member temporarily in a desired position. 90 95

Having thus described my invention, its construction and mode of operation, what I claim and desire to secure by Letters Patent of the United States, is as follows:

1. In a linotype machine, the combination 100 of the distributing mechanism, the second elevator to convey the matrices thereto, and manually controlled locking means to hold the elevator temporarily in operative relation to the distributing mechanism. 105
2. In a linotype machine, the combination

of the distributor box A, and the second elevator G provided with the manually operated latch H adapted to engage the framework of the machine and hold the elevator 5 in operative relation to the distributor box, all for the purpose described.

In testimony whereof I hereunto set my

hand this 26th day of November, 1912, in the presence of two attesting witnesses.

CHARLES P. RUBLEY.

Witnesses:

GEORGE F. OLDROYD,
WM. W. JAMISON.
